(57) CLAIM

I claim the ornamental design for a kayak, as shown and described.

DESCRIPTION

FIG. 1 is a perspective view of the kayak in use.

FIG. 2 is a perspective view of the kayak.

FIG. 3 is a side view of the kayak.

FIG. 4 is a top view of the kayak.

FIG. 5 is a bottom view of the kayak.

FIG. 6 is a front view of the kayak; and,

FIG. 7 is a rear view of the kayak.

The broken lines represent the environment in which the article resides and forms no part of the claimed design.
